Application January 28, 1942, Serial No. 423,541
In Great Britain January 29, 1941

2 Claims. (Cl. 299—119)

This invention relates to improvements in sulphur burning apparatus.

Many proposals have been made to produce sulphur dioxide by the combustion of molten sulphur which has been sprayed into air under suitable temperature conditions. In one apparatus for this purpose a spray burner is employed comprising a steam jacketed pipe terminating in a nozzle. Within the pipe there is provided an axially disposed rod having on the end near the nozzle a peripheral spiral of diminishing diameter ending in a needle point fitting into the orifice or the nozzle. Molten sulphur supplied under pressure to the jacketed pipe is forced through the orifice to emerge as a spray with a whirling motion imparted by the spiral, and by operating the axial rod the position of the needle relative to the orifice, and thus the feed of sulphur, can be regulated.

It is frequently found that such an apparatus is not entirely satisfactory because irregularities occur in the flow of sulphur and consequently in the production of sulphur dioxide. These irregularities can seriously affect the efficiency of any process, e. g. the manufacture of sulphuric acid, in which the sulphur dioxide is consumed. It is believed that the irregularities are in part due to difficulties in keeping the sulphur near the nozzle below a temperature at which it enters a viscous or plastic state, and in part due to partial carbonisation of the small amounts of bitumen which are normally present in naturally occurring sulphur, the carbonised bitumen causing blocking in the orifice. In the above type of apparatus such blockages can only be remedied by interfering with the setting of the orifice regulating the supply of sulphur, and thus resetting of the apparatus is required after each blockage.

According to the present invention we provide an atomizing device for molten sulphur comprising a jacketed tube having a short distance within one end an axially disposed orifice, means for supplying steam to the jacket, a longitudinally adjustable tube arranged coaxially within the jacketed tube terminating near the said orifice and dividing the said jacketed tube into an inner central channel and an outer annular channel, means for supplying compressed air to the central channel, means for supplying molten sulphur under pressure to the annular channel and means for regulating the position of the longitudinally adjustable tube relative to said orifice so as to regulate the supply of molten sulphur to the orifice. Advantageously, an axially disposed longitudinally adjustable rod is provided within the central channel terminating at the orifice in means for imparting a whirling motion to fluids passing through the orifice, together with means for adjusting the position of the said whirling means relative to the orifice.

Suitably the orifice is formed by a plug in the jacketed tube having an axially disposed hole flared on the inner face, and the longitudinally adjustable tube has a diameter intermediate between that of the maximum and minimum diameters of the flared portion. The disposition of the orifice within the jacketed tube serves to protect the region of the orifice from the full radiation from the flames formed on combustion of the spray, and thus the sulphur does not as readily enter the viscous state in passing through the orifice. The spacing of the orifice is not critical for this result to be achieved, but suitably the inner face of the plug is spaced within the jacketed tube by a distance between one and four internal diameters of the latter.

In using this apparatus the sulphur is delivered to the orifice through the space between the plug and the adjustable tube and the compressed air is supplied through the adjustable tube to bring about its atomization; by adjusting the position of the adjustable tube relative to the orifice and by regulating the supply of compressed air an adequate control of the sulphur spray can be attained. The spray exercises a cooling effect in the region of the nozzle and this, together with the shielding resulting from locating the orifice within the tube, enables the temperature in that region to be maintained low enough to prevent the sulphur from becoming viscous, and the bitumen from carbonizing. In the preferred form of our invention in which the central rod is provided terminating in means for imparting a whirling motion, a further fine adjustment of the sulphur spray can be obtained by moving the rod relative to the orifice. This same movement of the spiral also makes it possible to dislodge any partially carbonised bitumen which forms and sticks in the nozzle in spite of the improvements designed to repress this occurrence; thus the nozzle can be cleaned without interfering with the main adjustment of the sulphur supply. As a result of the improvements which constitute our invention, a steady production of hot molten sulphur spray can be maintained for greatly extended periods, so that the production of sulphur dioxide can itself be conducted in a more efficient manner than hitherto.

One form of apparatus according to the invention is shown, chiefly in section, in the accompanying drawing.

In this drawing 1 represents a cylindrical tube, having a jacket 2 through which steam can be circulated at any desired temperature by means of inlet 3 and outlet 4. Suitably these tubes and the other parts of the atomizer are of mild steel. Near one end of the tube 1 is a metal plug 18 having an axial orifice flared at each end, the flare on the inside being deeper than that on the outside to accommodate the whirling device referred

to subsequently. The plug is situated so that the end of the steam jacket extends beyond the inner side of the orifice by about $1\frac{1}{2}$ times the diameter of the jacketed tube 1, thereby protecting that region from the extremely high temperatures existing just beyond the tube where the sulphur ignites. Tube 1 has an inlet 5 through which molten sulphur can be supplied under pressure by means not shown. The temperature of the inlet pipe can be maintained by a steam jacket continuous with jacket 2 surrounding tube 1.

At the end of tube 1 is a flange 6 to which is bolted end plate 7 carrying an air tube 8, the gasket 19 ensuring an airtight connection. On the outer face of the end plate 7 is a centrally disposed stuffing box 9 and a straddle 10, in the top of which is a hole threaded to engage the externally threaded portion of a short tube 20 rigidly attached to hand wheel 11. Tube 8 passing movably through tube 20 and stuffing box 9 extends into tube 1 almost to the inner flare of plug 18, and is of slightly less diameter than the widest portion of that flare. Collars 21 and 22 are rigidly attached to tube 8 one immediately beyond either end of tube 20 and thus by rotating wheel 11 the end of tube 8 can be made to approach or recede from the flared orifice in plug 18, and the flow of molten sulphur from tube 1 through the orifice thereby regulated.

An inlet 12 for compressed air is provided in a portion of the tube 8 extending outside of tube 1, and at the end of the tube 8 is a stuffing box 13 through which a rod 14 passes into it, and extends down to the end adjacent to the plug 18. Rod 14 has on its end an external triple spiral thread 15 part of which is inside tube 8 and part of which is within the flared portion of the orifice in plug 18. At the other end of rod 14 is a handle 17 by which rod 14 and thus spiral thread 15 can be rotated or moved longitudinally. The atomizer carries a plate 16 by which it can be fixed in position in a sulphur burner.

In using this apparatus it is fixed in position in a sulphur burner, and the air tube 8 is adjusted to leave a small annular gap between its outside surface and the surface of the flared orifice. Steam at a suitable pressure is then supplied to the jacket 2 to maintain the latter at a temperature at which the molten sulphur is mobile, e. g. at 135° to 150° C. Compressed air is next supplied to inlet 12 and then molten sulphur is supplied under a less pressure through inlet 5 to the annular channel between tubes 1 and 8. The compressed air may, if desired, be preheated, e. g. at a temperature up to 300° C., or it may be supplied cold, in which case it will be heated by the surrounding jacket of molten sulphur; in passing between the individual threads of the member 15 and the orifice in plug 18 the air causes molten sulphur flowing through the annular gap between tube 8 and plug 18 to be entrained and atomized and thus pass into the combustion chamber as spray. The combustion chamber (not shown) is, of course, provided in the customary manner with a supply for the remainder of the air necessary to burn the sulphur, and with appropriate conduits to remove the sulphur dioxide produced.

The regulation of the sulphur supply in accordance with requirements can be made by altering the size of the gap between tube 8 and plug 18 by operating wheel 11; this will be a fully adequate control for most purposes, al-

though where a fine regulation is needed this can be done by adjusting the position of the spiral threads 15, by operating handle 17. Because the orifice in plug 18 is shielded from the heat of the burning sulphur in the combustion chamber by the projecting portion of steam jacket 2, the formation of carbonised bitumen or viscous sulphur in that region will be unlikely, and the main cause of irregularities in supply will be largely suppressed. If, however, such blockages do occur, they may readily be cleared by the operation of handle 17. Such clearing step can be made without altering the position of tube 8 relative to plug 18, and thus without disturbing the main setting of the atomizer. Using this apparatus we have found that the variations in the sulphur supply can be kept to within about 1%, whereas in types of atomizer previously in use, variations of the order of 25% were not uncommon.

I claim:

1. In an atomizing device the combination which comprises a tube having means defining an axially disposed orifice flared at its innermost end, a second tube having an inside diameter greater than the diameter of said orifice arranged axially within the first-named tube thereby to provide a central channel for compressed gas and an outer annular channel for liquid, said inner tube having an end terminating near said orifice in a conical portion conforming to the shape of said flared portion of the orifice said end having an inside diameter greater than the diameter of said orifice, means whereby said inner tube may be adjusted axially with respect to said orifice as required to adjust the flow of liquid from said annular channel through said orifice, a rod extending from the exterior of said device axially through said second-named tube and terminating adjacent said orifice, said rod being free of obstructions to the flow of gas in said tube and being slidably mounted for reciprocation to and from said orifice, and a tapered screw attached to the terminal end of said rod adapted to be positioned by reciprocation of said rod with its point in said orifice and its base in said second tube whereby the air and the liquid of the comingled air and liquid are caused to whirl.

2. In an atomizing device the combination which comprises a tube having means defining an axially disposed orifice, a second tube having an inside diameter greater than the diameter of said orifice arranged axially within the first-named tube thereby to provide a central channel for compressed gas and an outer annular channel for liquid, said inner tube having an end terminating near said orifice, said end having an inside diameter greater than the diameter of said orifice, means whereby said inner tube may be adjusted axially with respect to said orifice as required to adjust the flow of liquid from said annular channel through said orifice, a rod extending from the exterior of said device axially through said second-named tube and terminating adjacent said orifice, means whereby said rod may be adjusted axially with respect to said orifice, and a tapered screw attached to the terminal end of said rod adapted to be positioned by adjusting said rod with its point in said orifice and its base in said second tube whereby the air and the liquid of the co-mingled air and liquid are caused to whirl.

HECTOR GLYNDWR JAMES.
